Application February 25, 1938, Serial No. 192,632

2 Claims. (Cl. 2—71)

This invention relates to wearing apparel for women, misses and children.

More particularly, the invention has for one of its objects the provision of a garment for women which will allow complete freedom in the use of the limbs by providing a bifurcated drape portion simulating masculine attire without sacrificing feminine fashion and without resorting to garments of the convertible type.

Another object is to provide a bifurcated garment made of a continuous piece of material in which the leg portions can be quickly closed to simulate a skirt by the use of a portion of the material of the legs.

A further important object is to provide a bifurcated garment in which the legs are joined from the front waistline to the rear waistline by a single seam, the meeting edges of which are secured by a separable fastener along the entire length of the seam. By means of this construction, means are provided for enabling the wearer to quickly and conveniently perform the various natural functions of the body with ease and comfort.

For a more complete understanding of the invention reference is made to the accompanying drawings which illustrate a preferred embodiment of the invention.

Figure 1 is a front elevational view of the garment as it appears when worn, the pleated portions being secured to simulate a skirt.

Figure 1b is a view similar to that of Figure 1, showing the pleated portions parted to expose the leg portions of the garment.

Figure 2 is a rear elevational view showing the garment as worn, with the pleats folded in the manner shown in Figure 1.

Figure 3 is a front view showing the operation of the slide fastener at the front of the crotch.

Figure 3a is a rear view showing the operation of the slide fastener at the rear of the crotch.

Figure 4 is a view taken in the direction of the arrows along the line 4—4 of Figure 1, the legs being shown diagrammatically.

Figure 5 is a side view with one side of the drape portion cut away to show the separable fastener for the crotch extending from the waistline in front to the waistline in back.

Figure 6 is an elevational view of the blank used for the leg portions.

The invention includes an upper body portion 1, a waistline 2, and a lower drape portion 3. The drape portion, as shown in the drawings, has the appearance of a skirt, with lines flowing outwardly in flaring fashion from the waistline

to the bottom. The drape portion, while simulating a skirt, is comprised of bifurcated leg portions 4, 4a, which are preferably joined to the body portion at the waistline, and formed continuously therewith. The two leg portions are joined to each other along a seam 5 extending from a point 6 adjacent the midsection of the abdomen in front along the full length of the crotch to a point 7 adjacent the waistline in the back, as clearly shown in Figure 5. The adjacent edges of the leg portions along the crotch are provided with separable fastening elements 8 which are operated by a coacting slide fastener 9. By means of the slide fastener 9 the seam along the entire crotch may be opened quickly and conveniently for the performance of natural body functions.

The leg portions 4 and 4a are preferably arranged to simulate a skirt. For this purpose pleats 10, 10a are formed from the material of the leg portions by folding over upon itself a portion of the material of each leg along the full length thereof adjacent the opposite leg, with the meeting edges of the opposite pleats aligned in substantially abutting or overlapping relation.

Each of the leg portions 4, 4a has a portion cut out therefrom which begins at the top of the fastener 9, adjacent the midsection of the abdomen, and extends inwardly to the inner fold of the pleats 10, 10a, and upwardly to the top edge 30 of each leg portion, as best shown in Figure 6. An advantage of this construction is that it eliminates an additional thickness of material adjacent that portion of the body and lowers the fastening element to a point below the waistline 35 so as to avoid the discomfort caused by having a fastening element at the waistline when the wearer of the garment bends over.

As shown in Figure 1, fastening means are preferably provided to secure together the meeting edges of the adjacent front pleat portions, thereby enclosing and removing from view the seam 5 and separable fastener elements 8, so that the garment, simulating a skirt, may be 45 worn with the bifurcations exposed or enclosed, as desired, with complete modesty and propriety. The pleats at the back of the garment may be similarly fastened if desired. It will be seen that this construction provides a simple and effective garment which can be made and sold economically, and which can be used for wear around the house, for sportswear, or otherwise.

It is understood that changes in the construction of the garment may be made without de-
